UNITED STATES PATENT OFFICE.

LOUIS BINDER, OF NEWARK, NEW JERSEY.

BOX.

Application filed December 30, 1921. Serial No. 525,942.

To all whom it may concern:

Be it known that I, LOUIS BINDER, a citizen of the United States, and a resident of Newark, county of Essex and State of New Jersey, have invented certain new and useful Improvements in Boxes, of which the following is a specification.

This invention relates to an improved box, and is particularly adapted for cigar boxes which are made of heavy cardboard and which provide stability to the box to enable it to withstand the pressure of cigars being packed and pressed therein, and also provides a box that will withstand any warping due to the moisture in a humidor and the subsequent drying when the box is removed therefrom.

The invention is illustrated in the accompanying drawing, in which Figure 1 is a perspective view of the box with the lid open, the box being illustrated without ornamental covering and similar ornamentation that is put on the finished box. Figure 2 is a detail sectional view showing the juncture 25 of the bottom of the box and one of the wings that form the side walls thereof before they are bent or folded. Figure 3 is an enlarged section taken on line 3—3 in Figure 1, and Figure 4 is an enlarged section of 30 a corner of the box, taken on a plane indicated by the line 4—4 in Figure 1.

The body portion of the box is made of heavy cardboard, and in which the bottom 10 is integral with the front wall 11 and the rear wall 12, which I will call side walls, and the end walls 13 and 14, these side walls and end walls being bent up after the places that indicate their juncture have been slotted or cut, as at 15 in Figure 2, this cut extending up from the bottom and extending almost through the material, these folded walls then being subjected to vertical pressure so as to place them down edgewise alongside of the bottom 10, as shown in Figure 4. A bottom sheet 16 is then pasted over its entire surface to the bottom face of the bottom 10 and the bottom edges of the marginal walls, thus resisting any tendency of the bottom 10 to spring out again from 45 between the side walls.

The material is cut so that the grain of the fibre, indicated by surface shading in Figure 1, is longitudinal of the box, but this disposition of the fibre on the end walls 13 and 14 is vertical, so that outward pressure

on these walls, if they hold at the corners, splits or breaks the end walls easily, but this is overcome by pasting a sheet of slightly thinner cardboard 17 on the outer face of each end wall and having it project 60 from the end walls so as to engage the ends of the front wall 11 and the back wall 12, the fibre in the sheet 17 being at an angle, preferably a right angle, to the grain or direction of the grain in the end walls 13 65 and 14.

I find that a box made in this way is stable and less apt to break than the expensive old type of wooden box under the lateral pressure to which they are subjected when 70 cigars are pressed down in the box, as is now commonly done in packing cigars.

The projecting portions 18 of the sheet 17 limit any inward movement of the end walls 13 and 14, since these sheets 17 are securely 75 pasted to the outer faces of the end walls. An inner sheet 19 is usually pasted to the front wall on its inner face, and is inset from the end sufficiently so that the ends of the end walls abut against the ends of the 80 sheet 19, as will be seen from Figure 1.

The lid 20 is made of a central sheet 21 which is of relatively heavy material, and flanking sheets 22 and 23 which are pasted to the inner and outer faces of the central 85 sheet 21, the lid being attached to the back wall 12 by any suitable means, such as the strip of fabric 24. This form of lid insures a constant closure of the lid on the box all around, in contrast to the warping 90 that takes place in a wooden lid or a single sheet of cardboard forming a lid, especially when subjected to the alternate moisture and drying when the box is in or has been removed from a humidor, or under varying 95 climatic conditions.

I find that with a lid as described herein any warping is localized in the flanking sheets 22 and 23, and the only distortion that takes place is under moisture or heat, 100 these flanking sheets sometimes swelling or buckling away from the central sheet 21, but the central sheet is not affected since it maintains its rigidity and its stiffness and remains level, and the lid remains closed 105 at all points around its edges.

This form of lid also lends itself readily to holding a wooden strip 25 that is inserted in extension of the main sheet 21 of the lid and held by the flanking sheets 22 110

2
and 23, and through which a brad can be driven into a wooden block 26 placed in the recess 27 in the outer edge of the front wall 11.

5 I claim:

1. A box comprising a body portion made of one piece of heavy cardboard in which the side and end walls are bent up from the bottom portion, the front and back walls bearing on the ends of the end walls, and sheets secured to the end walls and projecting to engage the ends of the front and back walls.

10 2. A box comprising a body portion made of one piece of heavy cardboard in which the side and end walls are bent up from the bottom portion, the front and back walls bearing on the ends of the end walls, sheets secured to the end walls and projecting to engage the ends of the front and back walls,

15 20 and a sheet on the inside face of the front

wall and with its ends engaging the inside faces of the end walls.

3. A box comprising a body portion made of one piece of heavy cardboard in which 25 the side and end walls are bent up from the bottom portion, the front and back walls bearing on the ends of the end walls, sheets secured to the end walls and projecting to engage the ends of the front and back walls, 30 a sheet on the inside face of the front wall and with its ends engaging the inside faces of the end walls, the bottom being forced in between all the walls, and a retaining sheet on the outside of the bottom and secured 35 to the bottom edges of the side and end walls.

In testimony that I claim the foregoing, I have hereto set my hand, this 28th day of December, 1921.

LOUIS BINDER.
